Specification for Design.

Patented May 24, 1921.

Application filed September 16, 1920. Serial No. 410,768. Term of patent 14 years.

To all whom it may concern:

Be it known that I, CHARLES W. MANZEL, a citizen of the United States, residing at Buffalo, in the county of Erie and State of New York, have invented a new, original, and ornamental Design for an Oil-Gun, of which the following is a specification, reference being had to the accompanying drawing, forming part thereof, and in which—

Figure 1 is a side elevation of the oil gun embodying my design. Fig. 2 is a rear end view thereof. Fig. 3 is a front end view of the same.

I claim:—

The ornamental design for an oil gun, as shown.

CHARLES W. MANZEL.
